DUPLEX TRANSMISSION SYSTEM

Application filed March 27, 1926, Serial No. 97,877, and in France August 12, 1925.

The present invention relates to radio communication apparatus by means of which two transmissions are sent out simultaneously by one and the same antenna.

5 It has already been suggested for this purpose to divide the antenna used for transmission into two parts, and to compensate at the base the exchange or transfer currents between said two parts by the aid of inductive coupling of convenient kind between them. This scheme however, among other drawbacks, involves the inconvenience that, on account of the fact that but one half of the antenna is used for each transmission, 15 the aerial resistance is reduced.

The present invention has as its object to remedy the inconveniences in arrangements previously disclosed, by the simultaneous use for each of two transmissions of the entire 20 transmitting antenna. For this object two counterpoises are used provided in the neighborhood of each other and utilized to diminish in known manner the resistance of the aerial-ground circuit, and to play the part of capacity in an auxiliary resonant circuit, with the end in view of imparting to the aerial two resonance periods. The invention furthermore provides a simple arrangement adapted to prevent the flow of current from one of 25 the alternators into the other.

30 The basic idea of the present invention will be better understood by reference to the accompanying drawing in which

Fig. 1 is a circuit diagram of the arrangements, while

Fig. 2 shows an equivalent diagram in which the capacities between the counterpoises and between the aerial and each of the counterpoises are indicated in the form 40 of condensers.

45 Referring now to Fig. 1 an antenna is shown at A, having in its circuit a tuning inductance L_1 connected to an intermediate point of a second inductance L_2 , whose terminals are connected to different portions of a double counterpoise D. The two portions of the latter are placed close enough together so that the required electrostatic capacity exists between them as explained below. Two 50 alternators are shown at A_1 and A_2 designed

to generate respectively the two frequencies f_1 and f_2 to be transmitted. The alternator A_1 is connected to the antenna circuit by two inductive couplings M_1 and M_2 , the former being in the antenna lead-in wire while the latter comprises the inductance L_2 as one of its elements. The alternator A_2 is connected to the antenna by similar inductive couplings M_3 and M_4 .

55 The equivalent circuit diagram shown in Fig. 2 makes it clear that the system comprises, as a matter of fact, three circuits in electrostatic coupling relationship.

60 In this diagram the capacity between the two portions of the counterpoise is represented by C, and that between the aerial and each portion of the counterpoise by C_1 .

65 The operation of this arrangement is as follows:

If self-inductance coil L_1 is connected 70 exactly at the middle of coil L_2 , on exciting self-inductance coil L_1 by means of an oscillation generator, there is obtained a single resonance period which is independent of the value which C may be given, indeed, the latter 75 may be varied within wide limits without altering the current flowing through the self-inductance coil L_1 . This goes to show that points A and B, by virtue of symmetry, are at the same potential. But if the self-inductance coil L_1 is not connected exactly in the middle of coil L_2 , a very precise and definite value for condenser C will be found for which the current in coil L_1 undergoes a decrease. 80 This value of C corresponds to the condition 85 where circuit L_2C is tuned to the transmitter.

If, then, while not changing condenser C which is set to this value, the point of connection between coils L_1 and L_2 is varied, two frequencies will be obtained located upon 90 either side of the original frequency, in the presence of which a certain current flows in the coil L_1 . Moreover the farther the tap or connection at coil L_2 departs from the middle, the more these frequencies differ from the 95 mean frequency. Hence, the system has now two resonance frequencies. If, then, two equal couplings are provided at M_1 M_2 , current will be found to flow in inductance coil L_1 only for one of the two frequencies before 100

obtained, say, the lower one. If, next, one of the couplings is reversed, no current is found to flow any more in self-inductance coil L_1 for the lower frequency, but only for the higher frequency. This evidently goes to show that, for one sense of coupling of the coil M_2 , for instance, the reaction of the sender upon the system is zero. A current of this same frequency flowing through the system will furthermore not induce any electro-motive-force in the assembly of the two coils M_1 and M_2 .

In carrying the basic idea of the invention into practice, one of the two generators, A_1 , for example, is connected with the antenna-ground circuit by means of an electromagnetic coupling M_1 , and with the auxiliary circuit through the agency of a second electromagnetic coupler M_2 . The generator A_2 , on the other hand, is united by electromagnetic couplings M_3 and M_4 with the antenna-ground and the auxiliary circuit, respectively.

With proper connection of the four coupling means before-mentioned, it is thus possible to obtain and insure perfect independence of each of two transmissions, the frequencies of which correspond, respectively, to each of the two natural frequencies of oscillation of the radiating system. Contradistinct to what happens in an antenna divided into two parts, no interchange currents will be produced in the down-leads of the antennas; and these, as is well known, caused a considerable reduction in the effective height in the system previously disclosed.

The provision of the counterpoises is of the lowest possible cost, the potentials set up between the two parts of the counterpoise are not high, and this in turn means lower expense for insulation, while preserving the efficiency of operations at the same order of magnitude as in simplex working.

The fact that for each transmission the total capacitance of the wave radiating system is available contributes in large measure to an increase of the effectiveness of the system.

Having described my invention I claim:

1. A duplex transmission system comprising a single transmission conductor, means connected thereto for simultaneously imparting two resonant frequencies to the system and means for supplying energy to said system at each of said frequencies.

2. A duplex transmission system comprising a transmission conductor, means connected thereto to impart two resonant frequencies to the system, an energizing means for said system and means for coupling it thereto to permit energization at one of said frequencies and prevent energization at the other of said frequencies, a second energizing means for said system acting simultaneously with the

first and means for coupling it thereto to permit energization at the second of said frequencies and prevent energization at the first of said frequencies.

3. An antenna system comprising an antenna, an inductance having said antenna connected thereto intermediate its ends and a separate counterpoise connected to each end of said inductance, the capacity of these counterpoises forming with said inductance a resonant circuit.

4. An antenna system comprising an antenna, two unequal inductance sections each having one end connected to said antenna, a counterpoise connected to the other end of each of said inductance sections, said counterpoises forming with both of said inductance sections a resonant circuit.

5. A duplex transmission system comprising an antenna, an inductance having separate counterpoises connected to each end and forming therewith a resonant circuit, a lead connecting the antenna to an intermediate point of said inductance and two separate energizing means of different frequencies for energizing said system.

6. A duplex transmission system comprising an antenna, an inductance having a separate counterpoise connected to each end and forming therewith a resonant circuit, a lead connecting said antenna to an intermediate point of said inductance, two sources of high frequency current, inductive means for coupling each of said sources to said inductance, and means for coupling said sources to said lead.

7. A duplex transmission system comprising a single antenna, an inductance associated therewith through a variable connection, a counterpoise connected to each end of said inductance, the arrangement being such that said inductance and the capacity between counterpoises forms an auxiliary circuit possessing two resonant periods, and a pair of oscillation generators each coupled to both the antenna and said inductance for simultaneously energizing said antenna at both said resonant periods.
